UNITED STATES PATENT OFFICE.

PEARL V. BALL AND ROBERT H. WALLER, OF NASHVILLE, TENNESSEE.

AUTOMATIC IGNITION PLUG.

Application filed July 26, 1921. Serial No. 487,659.

To all whom it may concern:

Be it known that we, PEARL V. BALL and ROBERT H. WALLER, citizens of the United States, residing at Nashville, in the county 5 of Davidson and State of Tennessee, have invented a new and useful Automatic Ignition Plug, of which the following is a specification.

This invention relates to internal combustion engines, and is more particularly directed to an ignition plug for automatically igniting the combustible fluid in the combustion chamber of the engine.

An object of this device is to provide a 10 new and improved means of ignition by which the ordinary spark plug and an electrical ignition system may be entirely dispensed with, thereby greatly simplifying the engine and its operation and eliminating 15 many of the troubles arising from the operation of an automobile.

Heretofore, in attempting to replace the ordinary electrical system by a high compression plug, numerous springs and an additional cam shaft, operating rods and plungers have been added to the equipment of the engine in order to compress the combustible gases to a point where the gases are spontaneously ignited.

20 This invention contemplates the use of a plug, which, though non-electrical in character, has its ignition advanced or retarded from the steering wheel of the automobile in the same manner as in the case of an ordinary spark plug. The device is quickly and easily installed, since it is only necessary to remove the ordinary spark plug and secure the threaded projection of the ignition plug into the threaded opening provided for the 25 reception of the spark plug.

The device of the present invention requires none of the elements noted above, but is operated solely and controlled automatically by the different conditions arising in 30 the combustion chamber of the engine.

The invention will be best understood from a consideration of the following detailed description taken in connection with the accompanying drawing forming part 35 of this specification, with the understanding, however, that the invention is not confined to any strict conformity with the showing in the drawing, but may be changed and modified so long as such changes and modifications mark no material departure from

the salient features of the invention as expressed in the appended claims.

In the drawing:

Fig. 1 is an elevation of our improved automatic ignition device secured in the 40 spark plug opening of an internal combustion engine.

Fig. 2 is a vertical section of our automatic ignition device showing it mounted in the engine and illustrating the position 45 of the piston of the ignition device during a part of the compression stroke of the engine.

Fig. 3 is a similar section of the device 50 disclosing the position of the piston in the igniter during the intake stroke of the engine.

Fig. 4 is a plan view of the valve which 55 controls the communication between the combustion chamber of the engine and the firing chamber of the ignition device.

Referring to the drawing, 1 designates a 60 cylinder of an internal combustion engine, 2 the piston, and 3 the combustion chamber; these parts being of any approved construction as they form no part of our invention.

An auxiliary cylinder 4, which forms the 65 body of the ignition device, is provided with a reduced threaded lower end or projection 5, adapted to be screwed into the usual opening provided in the head of the engine for 70 the spark plug, making it unnecessary, in applying our device, to bore any additional openings in the cylinder or its head, or to add any extra elements for operating the device. The auxiliary cylinder 4 is provided 75 with a circumferential enlargement 6, forming with the reduced end of the cylinder a shoulder 7, and which in cooperation with the cylinder head, forms an annular seat for 80 a gasket whenever it is necessary to employ 85 one. The enlargement 6 also forms an annular shoulder 8 upon which rests the lower end of a sleeve 9, rotatably mounted upon the cylinder 4, and provided with an outstanding arm 10, connected to the usual operating rod 11 and controlled from the steering post of an automobile for advancing or 90 retarding the ignition.

A portion of the sleeve 9 is cut away to 95 provide an angular opening within the sleeve, the opening having two straight sides 12 and 13 at right angles to each other, and an inclined side 14 connecting the two sides 12, 13, said inclined side being adapted to 100 progressively cover or uncover the aligned 105 sides 12, 13, the inclined side 14 being inclined 110 to the horizontal.

openings 15 communicating with the cylinder 4. When the sleeve 9 is rotated upon the cylinder 4, as shown in Fig. 1, the openings 15 are progressively uncovered so that air 5 which is imprisoned in the cylinder 4 may be allowed to escape.

The cylinder 4 is closed at its upper or outer end by a threaded plug 19, the periphery of which is knurled for hand operation, 10 and has a piston 17 slidably mounted therein, said piston being of less length than the cylinder. The piston 17 is provided with a central bore 18 forming a firing chamber, into which projects a stationary rod or member 20, and when the piston 17 is reciprocated, the rod or member penetrates the bore 10 to a greater or less extent as Figs. 2 and 3 show. The piston 17 is provided with rings 21 located in grooves upon the outer periphery 20 of said piston to prevent the escape of gas from the combustion chamber 3 of the engine through the ports 15. The bore or chamber 18 is also provided with a circumferential groove in which is located a ring 22 to prevent leakage of gas from said bore 25 18.

The head or plug 19 has a central screw-threaded perforation into which is screwed the threaded portion 25 of the stationary 30 rod or member 20 provided with a knurled head 23 for turning the rod or member to adjust its position within the bore 18 so that the capacity of said bore may be increased or diminished.

35 The piston 17, at its lower end, is provided with a countersunk portion in which is seated a valve 26, having a conical boss 27 projecting upwardly from the center of said valve and adapted to fit a seat 28 40 formed at the lower end of the bore 18, and as shown in Fig. 2, closing the lower end of said bore 18 to the combustion chamber of the engine on the compression stroke thereof.

45 Angularly disposed perforations 29 are formed in the valve 26, and equally spaced around the base of the boss 27. The bottom of the piston 17 is counterbored forming a cage for the valve 26, said cage consisting 50 of the annular flange 30 and the inturned lugs 31. This construction permits the valve to be moved vertically for a limited distance, as shown in Figs. 2 and 3. At the bottom of the cylinder 4, is a conical chamber 33 having a reduced cylindrical portion 34 which 55 forms a communication between the combustion chamber 3 of the engine and the cylinder 4.

The operation of our device is as follows:—

It will be seen, from an inspection of Fig. 3 that the valve 26 is located in its lowermost position, permitting combustible gas to be drawn up through the perforations 29 65 and into the bore 18.

Upon the intake stroke of the engine piston, the piston 17 in the auxiliary cylinder 4 is drawn downwardly, causing a suction stroke in the bore or firing chamber 18, and as the valve 26 is acted upon, both by the force of gravity and the said stroke, it will descend to its lowermost position where it will rest upon the lugs 31. The combustible gas from the combustion chamber of the engine will be drawn through the perforations 29 70 75 into the bore 18 of the piston 17, as the movable piston is carried away from the stationary member 20.

Upon the return stroke of the piston 2 of the engine, the valve 26 will be forced in 80 close seating contact with the lower end of the piston 17, thereby cutting off communication between the bore 18 and the combustion chamber 3. The auxiliary piston 17 will be forced upwardly over the stationary 85 member 20 by reason of the compression of the gases in the engine, and the valve 26 being closed, the stationary member will compress the combustible fluid in the firing chamber 18 to such an extent that the gases 90 95 will be spontaneously ignited. When this ignition occurs, the pressure in the firing chamber 18 will rise considerably and force the valve 26 away from its seat upon the piston 17, and the burning gases from the 95 firing chamber 18 will be forcibly injected into the gases in the combustion chamber 3 of the engine, thereby igniting the gases.

When the piston 17 moves upwardly, the openings 15 provide escape ports for the air 100 contained in the cylinder.

Since air is driven out from the cylinder through the perforations 15, the piston 17 will be forced upwardly more rapidly and through a greater stroke than ordinarily 105 would happen if the air were not exhausted from the cylinder.

If at any time it should be found necessary to retard or advance the ignition, the sleeve 9 may be rotated so that one or more 110 of the perforations 15 will be covered or uncovered by the inclined wall or edge 14 of the slot formed in the sleeve 9.

If it be desired to advance the ignition of the gases in the firing chamber 18, the sleeve 115 9 will be so moved by the rod 11, which is connected to an operating lever on the steering wheel, that one or more perforations 15 will be uncovered by the sleeve 9.

If it be desired to delay the ignition, the sleeve 9 will be rotated in such a manner that some or all of the ports 15 will be covered by the sleeve 9, so that as the piston 17 is driven upwardly on the compression stroke of the engine, it will be resisted in its 120 upward movement by the air in the cylinder between the head 19 and the piston 17, and therefore it will be necessary for the piston 17 to compress this air in the cylinder while the member 20 is compressing the 125 130

gases in the firing chamber 18 and thereby delay the progress of the member 20 within the bore 18. Three degrees of retardation will be had, since there are three perforations 15 shown in Fig. 1, but any number of perforations may be formed in the cylinder 4 in order to get finer degrees of adjustment of the ignition device.

If it be found that the ignition always occurs too early in the cycle of the engine, no matter what adjustments have been made for the sleeve 9, the knurled head 23 may be rotated in a direction to cause the member 20 to be adjusted outwardly from the bore 18, whereby upon the next compression stroke of the engine, the member 20 will have a shorter travel within the bore 18. On the other hand, if the engine is fired late in the cycle of operation of the engine, the member 20 is screwed farther into the bore 18, thereby causing a greater length of the member 20 to be projected into the bore 18. When it is noted that the firing of any one cylinder is weak, the member 20 may be screwed into the bore 18 in order to diminish the compression space in the bore or firing chamber and thereby increase the compression.

During the exhaust stroke of the engine piston, the valve 26 will be seated and prevent exhaust gases from being pocketed in the firing chamber.

What is claimed is:—

1. In an internal combustion engine, the combination with an engine cylinder, of an auxiliary cylinder in communication with the engine cylinder, a piston movable in the auxiliary cylinder provided with a bore constituting a firing chamber, said piston being adapted to be operated by the compressed gases in the engine cylinder, a stationary member mounted in the head of the auxiliary cylinder and projecting into said bore, a valve carried by the movable piston and controlling communication between the bore and the engine cylinder, said bore being adapted to receive gases from the engine cylinder upon the suction stroke of the engine, escape ports provided in said auxiliary cylinder, and means for controlling said ports for regulating the speed of the movable piston during the compression stroke of the engine.

2. In an internal combustion engine, an igniter comprising a cylinder in communication with the engine cylinder, a piston operating in said igniter cylinder, a firing chamber formed in said piston, a stationary member mounted in the head of the igniter cylinder and adapted to be advanced or retracted in the firing chamber relative to the piston when the piston is operated, a valve movably mounted at the lower end of said piston and controlling communication between the firing chamber and the combustion

chamber of the engine, said valve permitting the firing chamber to receive combustible gases from the combustion chamber solely during the intake stroke of the engine piston, said gases being compressed beyond the ignition point during the compression stroke of the engine piston, the pressure in the firing chamber opening said valve.

3. In an internal combustion engine, an igniter comprising a cylinder in communication with the engine cylinder, a piston operating in said igniter cylinder, a firing chamber formed in said piston, a stationary member mounted in the head of the igniter cylinder and adapted to be advanced or retracted in said firing chamber relative to the piston when the piston is operated, a valve movably mounted in the lower end of said piston and controlling communication between the firing chamber and the combustion chamber of the engine, said valve remaining open to permit the firing chamber to receive combustible gases from the combustion chamber during the intake stroke of the engine piston, said gases in the firing chamber being compressed beyond the ignition point during the compression stroke of the engine piston, the valve being closed by the pressure in the engine cylinder.

4. In an internal combustion engine, an igniter comprising a cylinder in communication with the engine cylinder, a piston operating in the igniter cylinder, a firing chamber formed in said piston, a stationary member mounted in the head of the cylinder and adapted to be advanced or retracted in the firing chamber relative to the chamber when the piston is operated, a valve movably mounted in the lower end of the piston and controlling communication between the firing chamber and the combustion chamber of the engine, said firing chamber adapted to receive combustible gases from the combustion chamber during the intake stroke of the engine, said gases being compressed beyond the ignition point during the compression stroke of the engine piston, a series of perforations in the igniter cylinder, a sleeve rotatably mounted on the igniter cylinder and provided with a slot adapted to progressively uncover the aligned perforations in the cylinder for regulating the time of ignition of the gases.

5. In an internal combustion engine, an igniter comprising a cylinder in communication with the engine cylinder, a piston operating in said igniter cylinder, a firing chamber formed in said piston, a stationary member mounted in the head of the cylinder and adapted to be advanced or retracted in said firing chamber relative to the piston when the piston is operated, a valve movably mounted in the lower end of the piston and controlling communication between the

firing chamber and the combustion chamber of the engine, said firing chamber adapted to receive combustible gases from the combustion chamber during the intake stroke 5 of the engine piston, said gases being compressed beyond the ignition point during the compression stroke of the engine piston, and means for regulating the extent of projection of the stationary member into the 10 firing chamber.

6. In an internal combustion engine, an igniter comprising a cylinder in communication with the engine cylinder, a piston operating in said igniter cylinder, a firing chamber formed in said piston, a stationary member mounted in the head of the cylinder and adapted to be advanced or retracted in the firing chamber relative to the piston when said piston is operated, a valve movably mounted in the lower end of the movable piston and controlling communication between the firing chamber and the combustion chamber of the engine, said firing chamber adapted to receive combustible 20 gases from the combustion chamber during the intake stroke of the engine piston, said gases being compressed beyond the ignition point during the compression stroke of the engine piston, said valve comprising a disk 25 provided with perforations, a conical boss extending upwardly from the center of said disk and adapted to engage a seat at the lower end of the firing chamber for a portion of the compression stroke, but to be unseated 30 when the pressure in the firing chamber becomes sufficiently great to cause spontaneous ignition of the compressed gases in said chamber.

7. In an internal combustion engine, an 40 igniter comprising a cylinder in communication with the engine cylinder, a piston operating in said igniter cylinder, a firing chamber formed in said piston, a stationary member adjustably mounted in the head 45 of the igniter cylinder and adapted to be advanced or retracted in the firing chamber relative to the piston when the piston is operated, a valve movably mounted in the lower end of said piston and controlling 50 communication between the firing chamber and the combustion chamber of the engine,

said valve being adapted to open the firing chamber during the intake stroke and close said chamber during the compression stroke of the engine piston, the pressure in the 55 firing chamber when ignition occurs opening said valve.

8. In an internal combustion engine, the combination with an engine cylinder, of an auxiliary cylinder in communication with the engine cylinder, a piston movable in the auxiliary cylinder provided with a bore constituting a firing chamber, said piston being adapted to be operated by the compressed gases in the engine cylinder, a stationary member mounted in the head of the auxiliary cylinder projecting into said bore, a valve carried by the movable piston and controlling communication between the bore and the engine cylinder, said bore being adapted to receive gases from the engine cylinder upon the suction stroke of the engine, and a controllable air cushion in the auxiliary cylinder for regulating the speed of the movable piston during the compression stroke of the engine. 70

9. In an internal combustion engine, the combination with an engine cylinder, of an auxiliary cylinder in communication with the engine cylinder, a movable piston in the auxiliary cylinder provided with a bore constituting a firing chamber, said piston being adapted to be operated by the compression gases in the engine cylinder, a stationary member mounted in the head of 85 the auxiliary piston and projecting into said bore, a valve carried by the movable piston and controlling a communication between the bore and the engine cylinder, said valve adapted to be unseated by suction 90 in the engine cylinder, the relative movements of the movable piston and stationary member upon the suction stroke of the engine adapted to cause gas from the engine cylinder to be drawn into the bore in the movable piston.

In testimony, that we claim the foregoing as our own, we have hereto affixed our signatures.

PEARL V. BALL.
ROBERT H. WALLER.
